COMBINED TISSUE DISPENSER AND ACCESSIONARY TRAY

Esther Epstein, 5151 Buffalo, Apt. 24,
Los Angeles, Calif.

Filed Oct. 8, 1962, Ser. No. 72,028

Term of patent 14 years

(Cl. D52—2)

I claim:

The ornamental design for a combined tissue dispenser and accessory tray, as shown.
